UNITED STATES PATENT OFFICE.

ROSIA W. WELCH, OF BALTIMORE, MARYLAND, ASSIGNOR, BY DIRECT AND MESNE ASSIGNMENTS, TO ROYAL MILLING AND MANUFACTURING COMPANY, A CORPORATION OF MAINE.

RICE-POLISHING MACHINE.

SPECIFICATION forming part of Letters Patent No. 742,939, dated November 3, 1903.

Application filed October 29, 1902. Serial No. 129,191. (No model.)

To all whom it may concern:

Be it known that I, ROSIA W. WELCH, a citizen of the United States, residing at Baltimore, State of Maryland, have invented certain new and useful Improvements in Rice-Polishing Machines, of which the following is a specification.

This invention relates to improvements in rice-polishing machines.

Reference is to be had to the accompanying drawings, in which—

Figure 1 is a side elevation of the improved rice-polishing machine with the framework and the enveloping screen or casing in section 15 on the line 11 of Fig. 2. Fig. 2 is a horizontal sectional view taken on the line 2 2 of Fig. 1. Fig. 3 is an enlarged detail view of the skeleton frame or wheel designed to support the polishing-disk. Fig. 4 is a detail view of one 20 of said disks separate from its support.

Referring to the drawings, the letter A designates the machine-framework provided with upper and lower cross-beams $a a'$. Within the said framework and below the lower cross-beams a' are three step-bearings b , two of which are stationary and the other of which is vertically adjustable by being mounted on a pivot-beam b' , worked by means of a lighter screw b^2 , and to the upper cross-beams 25 a is secured a bracket c , provided with three shaft-bearings c' . Mounted to rotate in said upper and lower bearings c' and b are three vertical shafts d , one of which is provided with a driving-pulley d' and with two spur-gears d^2 , one of said spur-gears meshing with a similar spur-gear d^3 on one of the other shafts and the other spur-gear d^2 meshing with a spur-gear d^4 on the remaining shaft. Each of said shafts d carries a series of woven-wire polishing-disks B , one above the other, and the three series are arranged with their peripheries overlapping, as indicated in the drawings. Each of said disks is carried on a rimless-wheel support e , consisting of a hub 30 e' , adapted to fit on the shaft, and radial staggered spokes e^2 , and the woven-wire disk fits around the said hub and lies first above one spoke, then below the next spoke, and so on, thereby producing a circumferential sinuosity of the disk, as indicated in Fig. 1. Each 35 disk is provided with one or more radial slots f , as shown best in Fig. 4. The three series

of disks B are inclosed by a stationary shell C , comprising upper and lower circular heads $g g'$ and a screen h , of woven wire, supported 55 between said heads and two posts or brackets i and conforming to the outline of the series of disks, but spaced therefrom, as indicated in Fig. 2. Fig. 1 for the sake of clearness shows only a section of this screen. A hopper j is supported on the upper head g , and a discharge-spout l is connected to the lower head g' and is provided with a gate l' .

In practical operation a quantity of rice to be polished is fed into the hopper j and thence 60 passes onto the disks B , which are kept revolving in the direction of the darts, Fig. 2. In the actual construction of the machine the surfaces of the disks are close enough together to act with abrasion against the grains 65 of rice, which are thereby polished by such abrasion and also by attrition, and the rice finds its way down finally through the radial slots f and through the space between the disks and the screen h and is discharged out 70 of the spout l in a pearly-white condition. The dust and other small particles of impurities from the rice will be sifted out through the screen h . The disks B of one shaft may be raised or lowered whenever desired by 75 means of the lighter screw.

Having thus fully described my invention, what I claim as new, and desire to secure by Letters Patent, is—

In a rice-polishing machine, the combination of a plurality of vertical rotary shafts; a series of skeleton frames or wheels mounted one above the other on each shaft and provided with staggered spokes; woven-wire disks supported on said wheels and extending 85 alternately over and below said spokes whereby to produce a circumferential sinuosity, and the disks of one series overlapping the disks of the other series; means for rotating 90 said shafts; and a shell inclosing said disks 95 and provided with a woven-wire screen conforming to and spaced from the peripheries of the disks.

In testimony whereof I affix my signature in the presence of two witnesses.

ROSIA W. WELCH.
